CLAIM

The ornamental design for a sparkler fastener for bottles, as shown and described.

DESCRIPTION

FIG. 1 is a perspective view of the sparkler fastener for bottles, showing the new design in relation to a sparkler and a bottle neck;

FIG. 2 is a frontal view thereof;

FIG. 3 is a top view thereof;

FIG. 4 is a bottom view thereof;

FIG. 5 is a left-side view thereof; and,

FIG. 6 is a right-side view thereof.
